UNITED STATES PATENT OFFICE.

DAVID STEELE WALLACE, OF DENVER, COLORADO, ASSIGNOR TO THE WALLACE PLUMBING IMPROVEMENT COMPANY, OF SAME PLACE.

WATER-CLOSET.

SPECIFICATION forming part of Letters Patent No. 558,130, dated April 14, 1896.

Application filed January 30, 1895. Serial No. 536,678. (No model.)

To all whom it may concern:

Be it known that I, DAVID STEELE WALLACE, a citizen of the United States of America, residing at Denver, in the county of Arapahoe and State of Colorado, have invented certain new and useful Improvements in Water-Closets; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in water-closets, and especially to that class known as "double-trap siphon-closets."

The objects of my invention are, first, to provide a closet having the flushing-reservoir secured directly to the top of the closet or cast integral with it; second, to provide a closet which is retrapped directly from the city pressure, and consequently does not require a portion of reservoir contents at each flushing to retrap the bowl; third, to provide a closet adapted to receive the entire contents of the reservoir at each flushing; fourth, to provide a siphon-closet with deep traps; fifth, to provide a perfectly-noiseless closet and reservoir; sixth, to provide means to automatically regulate the flushing-valve to retrap the closet from the city water-supply; seventh, to provide a double-trap noiseless closet with an independent air-passage to the top of the reservoir; eighth, to provide a noiseless flushing-rim and reservoir attached directly to one another or cast integral, which can be attached to or cast on any make or design of bowl or arrangement of trap or traps at present in use. I attain these objects by the mechanism illustrated and described in the accompanying drawings and specification, in which—

Figure 1 represents a sectional elevation through the broken plane A of Fig. 3. Fig. 2 represents a sectional end elevation of the reservoir and a fragment of the closet, showing the operating mechanism therein, parts of which are shown in section. Fig. 3 represents a plan view of the closet and reservoir, drawn on a smaller scale. Fig. 4 represents an end elevation of the closet and a fragment

of the reservoir and shows in dotted lines the arrangement of the discharge-passage of the second trap. Fig. 5 represents the seat of 55 the flushing-valve. Fig. 6 represents a perspective view of the reservoir and closet cast integral.

Similar letters and figures of reference refer to similar parts throughout the several views. 60

Referring to Fig. 1, B designates the bowl of the closet. Its rim C is enlarged in the form of an oval. It has a water-passage C' formed in it, which is continuous around it. It is also open all around at its inner under 65 side at E, as shown. The water-passage extends backward into the body of the closet and registers with an aperture E' in the bottom of the reservoir F. This passage is controlled by a valve G and its seat G'. The 70 bowl B discharges into the discharge-passage H, which is arranged to extend backward from the front of the closet and upward to near the top of the closet. It is also diverged to one side of the longitudinal center of the 75 closet. It then curves downward to the base of the closet and then turns across the center and upward, forming a second trap, the bowl and the first part H of the discharge-passage to its highest point forming the first 80 trap.

I carry the first run of the discharge-passage as high as possible and the downward passage as far down as possible in the closet in order to get deep traps, and also a large volume of 85 water in the bowl and, in addition, a long siphon-leg H'. The second upward turn I of the discharge is carried up to get as deep a trap as possible and have its highest point below the lowest point of the first trap. It 90 then extends toward the front of the closet and opens out at the bottom of it at I', where the closet is flanged to connect to the soil-pipe. I provide the second trap with a vent-outlet I', by which this trap may be vented. 95 J is an air-passage formed in the top of the closet from the top of the first trap to the pipe K, which is secured to the reservoir and closet. It is provided with a perforation K', which is arranged to register with the air-passage 100 and continue it to the top of the reservoir F, or above the water-level. I arrange this air-pipe in reservoirs which are secured to the closets so that I can use it to take the place

of a bolt to secure the two together, as illustrated in most of the figures. To accomplish this, I thread the lower end, which is closed by a plug or other means, and provide it with 5 nuts L, arranging them to clamp the two together, as shown.

When the reservoir is separated from the closet, it is constructed of wood or other suitable material and lined with metal and must 10 be secured by bolts or other means to the closet; but when made of porcelain it is cast integral with it. The reservoir, when separate, sits directly on the closet, which is formed to project laterally on each side of its longitudinal center to make a base for it. A watertight joint is made between the two by inserting 15 a gasket M. I secure the reservoir to the closet preferably by the air-pipe K and also by the water-inlet pipe N, which is threaded 20 and provided with nuts similar to the air-pipe or valve-seat G', which has a third nut between the two. These two pipes are arranged at one end. At the opposite end, in place of using bolts, I preferably form the valve-seat 25 with two depending rods O and O', which extend through the closet. The ends of these rods are threaded and provided with nuts which are adapted to secure the closet and reservoir together. The body of the valve- 30 seat is threaded and provided with nuts M³, by which it is secured to the bottom of the reservoir.

The flushing-valve proper and seat, with the exception of the depending threaded rods, 35 are old; but in order that I may noiselessly flush the closet and use in so doing the entire contents of the reservoir and retrap the closet from the city pressure or other source of supply it is necessary to automatically control 40 it, so that it will remain open a short period of time after the closet has been flushed, and also so that it will close itself quickly and easily without that swash or wire-drawing noise being made by the water so common, as 45 the valve closes, in most closets. I preferably carry out this feature of my invention in the following manner: To the top of the valve I attach a weight P. To the valve-stem I pivot a lever Q loose enough to allow the 50 valve always to seat squarely. I pivot the lever on a shaft R, which I secure in any convenient manner in the reservoir. I illustrate it secured by pins in a U-slotted clip R', which is soldered to the metal lining of the reservoir. 55 In porcelain reservoirs this shaft would have to pass through its sides and be secured against leakage by suitable nuts and washers. To the opposite end of the lever I pivot a box X, which may be a water-containing receptacle of any suitable form. In the bottom of the box are made two perforations T and T'.

T is the water-inlet into the box, and it is made larger than T', which is the outlet. The inlet is controlled by a common clapper-valve 60 U, which operates to admit the water into the box through the perforation and retain it.

T' is a small perforation which is adjust-

ably controlled by a plate V, which is movably secured laterally over it by a screw V'. A perforation V² is made through the plate to 70 register with T'. By moving the plate laterally over the lower perforation I am enabled to partially close it, and thus regulate the time required to empty the box. As soon as the box is empty the flushing-valve is closed 75 by the weight. To the top of the box I secure a manually-operating push-rod 8, which is shown in Figs. 1 and 6. It extends up through the cover F' of the reservoir.

X' designates the overflow-pipe. It is 80 threaded to an opening in the valve-seat and communicates with the flushing-passage. It is also open to the atmosphere through the rim C when the closet is not flushing. N is the water-supply pipe, and N² its valve, which 85 is controlled as those in common use by the float N³.

The top outlet of the air-pipe K is provided with a valve Y, which is pivoted to a lever Z, pivotally supported in a bracket 1, which is 90 secured to the pipe. A depending rod 2 is pivoted to the opposite end of this lever and supports at its lower end a float 3, which operates to hold the valve open when the reservoir is full or is being filled with water. The 95 rod 2 is also supported by a bracket 4, attached to the pipe.

5 designates a casing, preferably a metal casing or box. It is adapted to fit over the air-pipe and also the overflow-pipe, although 10 it is not necessary that the overflow-pipe be placed under it, as I could vent the top of the casing by other means. The casing is airtight. It extends preferably to and rests on the bottom of the reservoir. One side, at 6, is cut away a short space above the floor at a predetermined point in proximity to the float 3 to allow the water to enter it freely and to exclude outside air from it until the water is below the said opening.

The operation is as follows: The water supply enters through the pipe N. The weight on the flushing-valve is sufficient to keep it closed when the box X is empty or nearly so. As the reservoir fills with water 11 it flows into the box through both of the perforations in its bottom, the larger one allowing it to fill as quickly as the reservoir. Normally the box is not full of water, the line 7 designating approximately its highest point 12 in the reservoir and box. To flush the closet, press down the rod 8, which pushes the box under water, filling it full, and thereby opening the valve, allowing the water to rush through the spider which supports its guide-stem into the flushing discharge-passage and closet-rim. The box being now full of water is heavier than the valve and holds it open. The water in the reservoir quickly runs out; but the water in the box runs out slowly through the small outlet T', which allows the water from the city pressure to flow into the reservoir, as its float has dropped and opened the valve with the discharge of the water. This

water passes through the valve and retraps the closet, and the small opening in the box is gaged so as to hold the flushing-valve open until sufficient water has passed through it to re-trap the closet. By this time the box is empty and the weight closes the flushing-valve, lifting the box again to its normal position. The air in the discharge-passage H' between the traps is removed and a siphon established by the outflowing water in the reservoir at the commencement of flushing, which creates a suction in the casing 5, that draws the air between the traps through the air passage and pipe, the valve being held open by the float 3, thereby creating a vacuum between the traps, creating a siphon in the discharge-passages H and H', which empties the closet. The overflow-pipe is closed to the atmosphere the instant flushing commences by the water passing through the discharge-valve and closing its outlet. As the reservoir refills the float 3 opens the air-valve Y and the air in the casing 5, which is compressed by the rising waters, finds an outlet through the overflow-pipe. The water flows from the reservoir through the passage C' around the rim C and disseminates evenly over the surface of the bowl through its annular opening E, thus flushing its entire surface.

I preferably make the bowl deep, as the large body of water it holds gives a more thorough flushing and a longer and better siphon than is usual, while the placing of the reservoir directly on the closet, or casting it as an integral part of it, obviates the use of pipes, and also makes the flushing noiseless. The oval hollow rim and top part of the closet containing the air-passage and air-pipe, the reservoir, the box, and water column for automatically closing the flushing-valve and regulating it so that the closet can be retrapped by the water-pressure can be applied to any arrangement or system of traps in water-closets at present in use. The holes 9 are used to secure a seat to the closet.

Having described my invention, what I claim as new, and desire to secure by Letters Patent, is—

1. The combination of a double-trap siphon water-closet having a flushing-rim, and a rearward table portion, a flushing-reservoir adapted to sit directly on said table portion, a flushing-valve seat secured in one end of said reservoir having two depending threaded rods carrying retaining-nuts and extending through said table portion of said closet, a water-inlet pipe and an air-pipe arranged in the opposite end of said reservoir to depend through said reservoir and through said table portion, and having threads and retaining-nuts upon their ends and adapted with said valve-seat rods and nuts to bolt the said reservoir to said closet, substantially as described.

2. A siphon-closet having the reservoir or flushing-tank secured to the body of the closet, a hollow flushing-rim open continu-

ously around the bowl, a water-passage in said closet connecting with said rim and with said reservoir, a valve arranged to control 70 said passage, a lever pivoted to said valve, a pivotal support in said reservoir for said lever, a box or water-receptacle pivoted to the opposite end of said lever, a water column flowing in and out of said receptacle intermittently an inlet-valve in the bottom of said box and an adjustable outlet-valve whereby the outward flow of water from said box may be regulated or timed, a manually-operated rod attached to said box and extending above 80 said reservoir for opening said flushing-valve, an air-passage in said closet extending above the water-level of said reservoir and connecting with the bowl-trap, a valve arranged to control the outlet of said air-passage, and an 85 air-tight casing in said reservoir surrounding said air-passage, substantially as described.

3. A double-trap siphon-closet having a discharge-passage at its bottom curving backward from the front of the bowl and upward, 90 also diverging obliquely to one side of the closet's longitudinal center, then turning downward to the base of closet, then laterally across the center and upward, and then toward the front of the closet and downward 95 and out near the center, a vent-outlet at the top of the second trap, a reservoir or flushing-tank secured directly to the body of the closet, substantially as herein shown, an air-passage 100 from the top of the first turn of the discharge-passage to the top of the reservoir, a hollow rim or other flushing device connected by a valve-controlled passage to the reservoir, and mechanism substantially as herein shown and described for automatically flushing said 105 closet, as specified.

4. The combination with a bowl, a siphon discharge-passage extending upward and diverging obliquely from its center, then turning vertically downward to the base and then 110 across the center and upward, and then downward to a soil-pipe connection arranged on the bottom of the closet, a vent-outlet at the top of the second trap, a reservoir or flushing-tank cast with the closet, thereby forming an 115 integral part thereof, an air-duct leading from the first bend of the siphon-passage to the reservoir, a pipe secured in said reservoir and closet provided with a side opening registering the said air-duct, and a valve-controlled 120 outlet to said pipe, substantially as described.

5. The combination in a siphon water-closet of a bowl provided with a hollow flushing-rim, a double-trap siphon discharge-passage arranged substantially as herein shown, an air-duct 125 communicating with the siphon-passage in the air-space between the two traps in the top of the closet, a reservoir or flushing-tank arranged and adapted to form an integral part of the closet and bowl, a pipe secured in said 130 reservoir provided with an outlet registering with said air-duct having its lower end closed, and at its upper end a valve arranged in operative engagement with the outlet, a lever

5 pivoted to said valve, a bracket supporting said lever, and attached to said pipe, a float secured to the opposite end of said valve-lever by an intermediate rod operating to close
10 said valve, a valve-controlled flushing-passage arranged in the closet and reservoir, a tilting lever pivoted at one end to said flushing-valve, a box or water-holding device pivoted to the opposite end of said lever, means
15 substantially as herein described for filling said box with water and regulating its outflow, an overflow-pipe connecting the top of said reservoir with the atmosphere through said rim and an air-tight casing in said reservoir inclosing said air-duct pipe and valve and overflow-pipe, all arranged substantially as herein described.

6. The combination of the reservoir and closet having said closet arranged and adapted to receive and support said reservoir as a
20 removable portion thereof, a water-passage from said reservoir to the bowl of said closet, a flushing-valve seat arranged to control the entrance to said passage and provided with

two depending rods extending through adaptable portions of said closet and threaded at the ends and retaining-nuts on said rods adapted to secure said reservoir to said closet as set forth.

7. The combination with the reservoir and closet of an air-pipe extending through said reservoir and closet having its lower end threaded and provided with nuts adapted to clamp the closet and reservoir together having its lower end closed, a side opening in said pipe, an air-duct in said pipe registering therewith and communicating with the air-space above the closet's first trap and an automatically-controlled valve arranged in operative engagement with the pipe's outlet in the reservoir, and a casing surrounding said air-pipe, substantially as described.

In testimony whereof I affix my signature in presence of two witnesses.

DAVID STEELE WALLACE.
